No. 687,765.

Patented Dec. 3, 1901.

A. J. LUNDVALL.
COMBINED SKIRT AND WAIST SUPPORTER.

(Application filed May 28, 1901.)

(No Model.)

UNITED STATES PATENT OFFICE.

ADELA J. LUNDVALL, OF TRINIDAD, COLORADO.

COMBINED SKIRT AND WAIST SUPPORTER.

SPECIFICATION forming part of Letters Patent No. 687,765, dated December 3, 1901.

Application filed May 28, 1901. Serial No. 62,233. (No model.)

To all whom it may concern:

Be it known that I, ADELA J. LUNDVALL, a citizen of the United States of America, residing at Trinidad, in the county of Las Animas and State of Colorado, have invented certain new and useful Improvements in Skirt and Waist Supporters; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to an improvement in skirt and shirt-waist supporters; and the objects of my invention are, first, to provide a skirt-supporter that will bring the weight of the skirt upon the corset; second, to provide a supporter that is pivotally attached to the corset in such a manner that the skirt is free to depend naturally from the corset, and, third, to provide a simple and cheap skirt-supporter by which a shirt-waist and a skirt can be instantly attached together or separated from one another. I attain these objects by the construction illustrated in the accompanying drawings, in which—

Figure 1 is a side elevation of my improved skirt and waist supporter. Fig. 2 is a section of Fig. 1 on line A. Fig. 3 is a fragmentary elevation of a modification of the skirt-supporting ring and of the button of Fig. 1. Fig. 4 is an end elevation of the fragment shown in Fig. 3. Fig. 5 is an edge elevation of a fragment of a corset and a shirt-waist and a skirt, showing my supporter operatively attached to the corset and the skirt and shirt-waist supported and held by it; and Fig. 6 is a side elevation of a fragment of a corset, a shirt-waist, and a skirt, showing the application of the supporter to the corset and skirt and shirt-waist.

Similar numerals of reference refer to similar parts throughout the several views.

Referring to the drawings, the numeral 7 designates a thin plate of any suitable material, such as brass or tin. To the lower side edge of this plate, close to its ends, I secure two buttons 8 and 9, the shank 10 of each of which is preferably provided with a shoulder 11, that rests against the plate. From the

shoulder 11 a rivet portion 12 projects through the plate and is riveted to it. A head 13 is formed on the outer end of the stem. This head is of larger diameter all around than the stem and is made oblong and preferably tapering from that portion immediately surrounding the stem upward toward the top edge of the plate, its length being preferably about twice its width. Its narrower end is rounded, and as the head is tapering it can be very readily inserted through a buttonhole formed in a shirt-waist. Over the oblong head of the button and on its stem I place a round ring 14, of any suitable metal, preferably using brass. This ring is made of small-sized round wire and is adapted to be sewed at one side to the skirt and to be hooked to and unhooked from the oblong-headed button at the will of the user. To the upper side edge of the plate and preferably closer together than the oblong-headed buttons, but at equal distances from them, I pivotally secure, by means of eyelet-rivets 15 and 16, two arms 17 and 18. These arms are pivoted to swing freely on the eyes. I use eyelet-rivets, as they are far superior to a plain rivet for connection. In the upper end of each arm I secure metal eyelets 19 and 20.

In Figs. 3 and 4 I show a modification of the ring and button-head. In these figures the upper terminal end of the head 13 is curved inward toward the plate 7 to form hook 13^A, and when the shirt-waist 21, a fragment of which is shown in Fig. 4, is buttoned over the head the ring is practically locked to the stem of the button against easy accidental displacement. The skirt-supporting ring in this modification is made substantially in the form of the figure 8 or double ring, the lower part 14^A of the double ring being adapted to be sewed to the skirt and the upper part to hook over the oblong-headed button.

In Figs. 5 and 6 I illustrate the supporter operatively attached to a corset 22, the ends of which are laced together by a lacing 22^A, which is inserted in the lacing-holes 22^B and supporting a skirt 23 and attached to a shirt-waist 21. The supporter is attached to the corset by being tied through the eyelet-holes 19 and 20 in the free ends of the arms 17 and 18 by lacing-cords 25 and 26 to the holes 22^B.

of the corset, a portion of the corset being broken away to show the cords and the ends of the arms tied to the corset. In attaching the arms to the corset eyelet-holes should be selected that will bring the skirt-rings underneath the waist-belt 28, a fragment of which is shown, so that the belt will cover the oblong head of the button and the skirt-ring. As the arms are secured at the top only, they are free to spread apart when the corset is unlaced and to hang freely when it is laced, which allows the plate and skirt to adjust themselves naturally. The skirt-rings are placed outside of and farther apart than the arms in order that the skirt may be more squarely held and depended evenly from the plate. The manner of supporting the skirt and of attaching the skirt-waist is as follows: The skirt-rings are sewed to the skirt, as shown in 15^a in Fig. 6, and the plate and arms are releasably tied from the opposite eye-holes of the corset by the lacing-cords, which are made long enough to allow the top ends of the arms to be tied close up even with the eye-holes in the corset or to be let out so the ends of the arms will hang down at any desired point below the eye-holes they are tied to. The skirt is then hooked over the oblong heads of the buttons. The shirt-waist, which is provided with longitudinal buttonholes 29 and 30, is then buttoned over the oblong heads. The belt is then placed over the supporter. It requires but an instant to button or unbutton the shirt-waists, to hook or un-

hook the skirt. The eyelets are pressed into the holes 31, 32, 33, and 34, which are formed through the ends of the arms and through the plate before the eyelets are inserted. The eyelets in the free end of the arms are pressed in tight, but those that join the arms to the plate are pressed to form a pivotal joint.

My invention is simple, strong, and durable and enables skirts and shirt-waists to be changed without changing the supporter.

Having described my invention, what I claim as new, and desire to secure by Letters Patent, is—

The combination in a skirt-supporter and shirt-waist holder of a plate, two arms pivotally attached at one end to one edge of said plate near its opposite ends and the opposite end of each arm containing an eyelet-hole, a lacing-cord in the eyelet-hole of each arm, adapted to be tied to the eyelet-holes of a corset, said plate having a button comprising a projecting stem secured to the lower edge of the plate near each opposite end, and an oblong tapering head extending upward formed on the end of said stem, having an inward curve in its narrow end and a ring adapted to hook over the oblong heads of said buttons, substantially as described.

In testimony whereof I affix my signature in presence of two witnesses.

ADELA J. LUNDVALL.

Witnesses:

BESSIE THOMPSON,
G. SARGENT ELLIOTT.
